Robert D. Cranston Inventor,
By Attorney *E. A. Kelly*.

UNITED STATES PATENT OFFICE.

ROBERT D. CRANSTON, OF READING, PENNSYLVANIA.

LAMP-GLOBE HOLDER.

SPECIFICATION forming part of Letters Patent No. 716,673, dated December 23, 1902.

Application filed August 20, 1902. Serial No. 120,285. (No model.)

To all whom it may concern:

Be it known that I, ROBERT D. CRANSTON, a citizen of the United States, residing at Reading, in the county of Berks and State of Pennsylvania, have invented certain new and useful Improvements in Lamp-Globe Holders; and I do hereby declare the following to be a full, clear, and exact description of the invention, such as will enable others skilled in the art to which it appertains to make and use the same.

This invention relates to improvements in lamp-globe holders; and the object of the invention is to overcome the danger of the globe being knocked or tilted from the holder.

The invention consists in forming the flange of the globe with a series of slots adapted to engage tongues on the holder.

The invention is fully described in the following specification, and clearly illustrated in the accompanying drawings, in which—

Figure 1 is an elevation showing a lamp-globe in position in my improved holder. Fig. 2 is a plan view of the holder itself.

The holder A may be of any desired form, preferably circular, the outer portion *a* thereof being adapted to receive the flange of the globe. This portion *a* of the holder is formed with a series of equidistant integral projections *b*, which projections are bent upward at right angles to the face of the holder and inward toward the vertical center of the holder and then bent back on themselves to form spring-tongues *b'*, as shown in Fig. 1 of the drawings.

The globe B may be of any shape or size and is formed with a flaring mouth or flange *e* at its bottom adapted to rest on the portion *a* on the holder A. This flaring mouth or flange of the globe is formed with a series of equidistant slots *f*, corresponding in number and distance with the projections on the holder and adapted to register therewith. When the globe is

placed in position on the holder, the slots *f* will when the globe is turned thereon register with said projections, permitting them to enter said slots and allow the globe to seat itself in proper position in the holder. The globe is then turned slightly in either direction sufficient to prevent the projections from registering with said slots and to allow the spring-tongue of each projection to bear against the incline face of the flaring mouth or flange. The globe will then be locked effectively in position in the holder and all danger of being knocked therefrom or tilted out of position will be removed. The upper face of the holder is perfectly flat, and the globe is held entirely in position by the spring-tongues *b'* on the projections *b*. The easy removal of the globe of course is evident.

Having thus fully described the invention, what I claim, and desire to secure by Letters Patent, is—

A device of the class described consisting of a body portion provided with a flat unobstructed upper face, and a plurality of projections integral therewith, each of said projections extending upward from the periphery thereof and at an angle to the plane of the upper face, said projections inclining toward the diametric center of the holder and being bent back upon themselves to form spring-tongues, and a globe provided with a mouth or flaring flange, a plurality of slots in the flange adapted to allow the projections to pass therethrough and the spring-tongues to engage the outer face of the flanged mouth at points intermediate said slots.

In testimony whereof I affix my signature in presence of two witnesses.

ROBERT D. CRANSTON.
